CLAIM

The ornamental design for a dispenser for toilet tissue, as shown and described.

DESCRIPTION

FIG. 1 is a front, side and top perspective view of a dispenser for toilet tissue showing our new design.

FIG. 2 is a front view thereof.

FIG. 3 is a rear view thereof.

FIG. 4 is a top view thereof.

FIG. 5 is a bottom view thereof.

FIG. 6 is a left side view thereof; and,

FIG. 7 is a right side view thereof.

The broken lines shown in some of the figures show portions of the dispenser for toilet tissue that form no part of the claimed design.

1 Claim, 7 Drawing Sheets
